UNITED STATES PATENT OFFICE.

PETER BALZANO, OF NEW HAVEN, CONNECTICUT.

CUE-TIP.

1,089,812.

Specification of Letters Patent. Patented Mar. 10, 1914.

Application filed February 14, 1913. Serial No. 748,370.

To all whom it may concern:

Be it known that I, PETER BALZANO, a subject of Victor Immanuel III, King of Italy, residing at New Haven, in the county 5 of New Haven and State of Connecticut, have invented certain new and useful Improvements in Cue-Tips, of which the following is a specification, reference being had therein to the accompanying drawings.

10 My invention relates to a new and improved cue tip, having for its object, among other things, to construct the tip so that it may be used with my improved mechanism for securing the same to a cue, as set forth 15 in Letters Patent of the United States No. 1,046,871, issued to me December 3, 1912, and which will enlarge the scope and usefulness of said mechanism, that is, enable it to be used for tips that are not at present 20 adapted thereto.

To these, and other ends, my invention consists in the cue tip, having certain details of construction and combinations of parts, as will be hereinafter described and 25 more particularly pointed out in the claims.

Referring to the drawings, in which like numerals of reference designate like parts in the several figures; Figure 1 is a sectional view of the end of a cue with my improved tip attached thereto; Fig. 2 is an enlarged 30 fragmentary sectional view of the tip; and Fig. 3 is a view of the anvil washer.

I have shown, in Fig. 1, a sectional view of the end of a billiard cue, which is designated by the numeral 1, upon the end of which is fixed the ferrule 2, having a stud 3 thereon, onto which is threaded the base block 4, having prongs 5 thereon. The base block herein shown is of substantially the 35 same construction as that shown in the patent above referred to, and is applied to the stud 3 in the manner therein described. The stud 3 is of such length that it projects slightly beyond the face of the base block. 40 The tip 6 is of the usual form and provided

with an annular recess 9 in its flat face, in the bottom of which is the anvil washer 7 that surrounds the core 8.

When the parts are assembled the prongs 5 on the base block project into the tip 6, 50 through the recess 9 as shown in Fig. 1, and the core 8 is in contact with the end of the plug 3, which is slightly advanced beyond the front face of the block 4, as above described, thereby providing an unyielding 55 backing for substantially the entire flat face of the tip.

Having described my invention, what I claim as new and desire to secure by Letters Patent, is:—

1. In combination, a cue; a cue tip, having a recess in the flat face thereof surrounding a central core; an anvil washer in the bottom of said recess; a ferrule upon 60 said cue, having a stud therein that contacts with said core; and a pronged base block mounted upon said stud with its outer face slightly below the end of said stud.

2. In combination, a cue; a ferrule connected therewith, having a stud thereon; a cue tip, having a recess in its flat face surrounding a core, the axis of which is coincident with that of said stud; an anvil washer within said recess; a base block, having prongs thereon, connected with said stud 65 so that the outer face thereof is slightly below the end of said stud, said prongs being so arranged that they enter said recess and are turned outwardly and into the said tip when they engage said anvil washer and 70 hold said tip with its flat face against the end of said stud and the face of said base block, the various flat portions of said face of said tip then occupying different planes.

In testimony whereof I affix my signature 75 in presence of two witnesses.

PETER BALZANO.
